UNITED STATES PATENT OFFICE.

FRANCIS R. HOYT, OF EAST ORANGE, NEW JERSEY, ASSIGNEE TO THE SIMMS MAGNETO COMPANY, OF EAST ORANGE, NEW JERSEY, A CORPORATION OF NEW YORK.

SELF-CONTAINED HIGH-TENSION BATTERY IGNITION-UNIT SYSTEM.

1,216,124.

Specification of Letters Patent. Patented Feb. 13, 1917.

Application filed April 28, 1916. Serial No. 33,376.

To all whom it may concern:

Be it known that I, FRANCIS R. HOYT, a citizen of the United States, residing at East Orange, in the county of Essex and State of New Jersey, have invented certain new and useful Improvements in Self-Contained High-Tension Battery Ignition-Unit Systems; and I do hereby declare the following to be a full, clear, and exact description of the invention, such as will enable others skilled in the art to which it appertains to make and use the same.

My invention consists in the novel features hereinafter described, reference being had to the accompanying drawings which show several forms in which I have contemplated embodying my invention, selected by me for the purpose of illustrating the invention, and the said invention is fully disclosed in the following description and claims.

In the said drawings:

Figure 1 is a diagrammatic view illustrating a system embodying my invention, parts of the system being indicated by conventional representations of their physical embodiments instead of by symbols, for greater clearness.

Figs. 2, 3 and 4 are similar views representing modified forms of my invention.

In the installation of battery ignition systems it has been customary in many instances to employ an induction coil usually mounted upon the dash board, where the mechanism is installed in a motor vehicle, but in practically all instances at a considerable distance from the battery and from the periodic interrupter, thus necessitating a complicated system of wiring with a considerable number of exterior wires, which can and frequently do become broken, and connections therefor, which can and frequently do become loose, the breaking or loosening of any of which is likely to interfere with the operation of the internal combustion engine with which the ignition system is installed, and it is very difficult in practice to locate troubles caused in this way.

In such cases, it is also customary to employ a condenser in connection with the induction coil, and this is ordinarily located adjacent to the coil necessitating long connections to the contact points of the periodic interrupter across which the condenser is

inserted so that the resistance in such wires interferes in a degree with the operation of the condenser.

One of the objects of my present invention is to correlate and assemble in close proximity all of the parts or elements of the system except the battery and spark plugs, so as to form a unit, the parts of which are electrically connected with respect to each other at the factory by very short wires, within the confines of the unit itself, which will not be liable to be broken or become disconnected. I also prefer to provide for grounding one end of the primary circuit so that it will be only necessary to connect a single wire from the battery to the ignition unit, and to connect the distributor contacts to the spark plugs, thus reducing the exterior wiring to a minimum. This arrangement of the elements in the unit also enables me to locate the condenser in close proximity to the contact points of the periodic interrupter and to the induction coil.

I also prefer in assembling the various parts into a single unit as hereinafter described to connect all of the rotary parts of the several elements for joint rotation, and to hold them in fixed relation with respect to each other, and I also prefer to connect the non-rotary parts of the several elements of the unit so as to hold them in substantially fixed relation with respect to each other while permitting a slight movement of said connected parts or of the necessary elements thereof, in a rotary direction with respect to the axis of rotation of the rotary parts to permit of the advancing and retarding of the spark.

I also prefer to employ in the unit a commutator for automatically reversing the direction of the current in the primary winding, for the purpose of preventing a transfer of metal from one contact point to the other of the periodic interrupter for preserving and lengthening the life of the said contact points and maintaining the apparatus at all times in operative condition.

In the accompanying drawings, I have shown several embodiments of my invention, which I have selected for purposes of illustration, and which show various ways in which the several elements of the unit can be combined, and I have illustrated my invention as applied in all these modifications.

to a high tension battery ignition system provided with means for changing the direction of the primary current across the contact points of the periodic interrupter 5 at intervals during each revolution of the rotary parts.

As indicated in these figures, the ignition unit comprises a distributer for directing the secondary current to one or other of the 10 spark plugs of the engine, a periodic interrupter, and a commutator, each having non-rotatable as well as co-acting rotatable parts, and being associated with an induction coil, and a condenser, all the rotatable 15 parts being connected for joint rotation, the non-rotatable parts being connected and held in substantially fixed relation with each other, but being capable of rotary movement to effect the advance and retard 20 of the spark, the coil and condenser being associated in certain of the forms herein shown with the said rotatable parts, and in other forms being associated with the non-rotatable parts according to the manner in 25 which the various elements of the unit are grouped and associated.

In Fig. 1 of the accompanying drawings, for example, I have shown diagrammatically 30 an ignition system in which the various parts hereinbefore referred to are associated in the form of a unit in which the induction coil as well as the condenser are associated with and adapted to rotate with the rotatable parts of the periodic interrupter, commutator 35 and distributer. In this figure the periodic interrupter is shown as comprising a non-rotary cam ring, 1, and a rotary part, 2, carrying the fixed contact, 3, the movable contact, 4, the latter being mounted on a 40 pivoted bell crank lever, 5, and provided with the usual fiber heel, 6, for engaging the actuating portions of the cam to separate the contacts which are otherwise held together by the spring, 7.

45 The commutator comprises stationary contact plates 8 and 9, and the rotary parts thereof are the commutator brushes 10 and 11, which, in this instance, are mounted on the rotary part, 2, which also carries the 50 rotary portion of the periodic interrupter.

The distributer comprises stationary contacts, 12—12—12—12, and the rotary portion, which, in this instance, is a block or plate 13, adapted to rotate in a path 55 contiguous to the contacts, 12, so as to permit the spark to jump from said plate to the several contacts of the distributer.

14 represents the core of the induction coil which may, however, be of any preferred construction and is provided with a primary winding indicated at 15, and a 60 secondary winding indicated at 16. 17 represents the condenser which is, in this instance, interposed between the coil and the 65 periodic interrupter. The arrows in the

figure indicate which parts are rotatable and also the direction of rotation, and it will be understood that the rotatable parts of the periodic interrupter, the commutator, and the distributer, are suitably connected together and to the induction coil and commutator as indicated by dotted lines, Z, so that they all rotate in unison and preferably on a common shaft and are held normally in fixed relation to each other. The non-rotary parts of the periodic interrupter, the commutator and the distributer are also held in fixed relation with each other, as indicated by the dotted lines, X, but are preferably so arranged in practice that they may be oscillated to a limited extent with respect to the axis of rotation of the rotary parts as by means of a timing lever indicated at Y in Fig. 1 for the purpose of advancing or retarding the spark. 70 75 80 85 90

18 represents the battery or accumulator and 19—19—19—19 represent the spark plugs. The circuit connections are as follows: The battery, 18, is grounded as indicated by the wire, 20. A single wire, 21, 95 leads from the battery to the contact plate, 8, of the commutator. The course of the primary circuit, when the parts are in the position shown in Fig. 1, will be as follows: from the battery over wire, 21, to contact 100 plate, 8, thence to commutator brush, 11, thence to the movable contact, 4, which is electrically connected therewith, thence to the fixed contact, 3, thence to the commutator brush, 10, which is electrically connected therewith, thence to contact plate 9 of the commutator, thence by brush indicated at 22, on a portion of the plate, 9, concentric with the axis of the rotary parts to a metallic part, as the screw, 23, carried by 105 the rotary part, 2, thence by wire, 24, to the primary coil, 15, thence to ground returning therefrom to battery.

The condenser is connected by wires, 25—26, between the brushes, 10 and 11. 110 The secondary current generated in the secondary coil, 16 will pass to the distributer block or plate, 13, thence to one or other of the distributer points, 12, and thence by wires, 27—27—27—27 to the respective 115 spark plugs, 19. It will be understood that as the brushes 10—11 pass from one contact plate to the other the path of the primary current between the fixed and stationary contacts of the periodic interrupter will be 120 reversed, that is to say, after each half revolution of the rotary parts, or after the production of two sparks, where, as in the case illustrated, the distributer is connected with four spark plugs for operating a four cylinder engine.

As will be seen all the wiring between the several parts of the unit is interior wiring which can be installed at the factory where the parts are manufactured and as. 125 130

sembled, permitting the use of very short wires, and the soldering of connections where desirable so that the danger of any of these interior wirings becoming loosened or broken is reduced to the minimum. It will also be seen that in installing this unit in connection with internal combustion engines, it is only necessary to connect a single wire, 21, from the battery to the commutator plate, 8, and the four wires, 27, from the distributor points to the respective spark plugs, thus reducing to a minimum the exterior connections, it being understood that the ground connection from the primary 15 coil here illustrated by the wire, 28, will ordinarily be made within the apparatus to the metallic portions thereof, and thence to the engine body.

In Fig. 2 of the accompanying drawings, 20 I have shown a modification of my unit system in which the contacts of the periodic interrupter and the brushes of the commutator are stationary and the operating cam for the interrupter, and the contacts of the 25 commutator rotate, and in this figure I have also illustrated a slightly different grouping and arrangement of the different parts. Thus in this figure 101 represents the rotating cam of the periodic interrupter, 103 the 30 fixed contact, 104 the movable contact carried by the lever, 105 having fiber heel 106 for engaging the cam, the said lever and contacts being stationary and provided respectively with the commutator brushes, 35 110—111, which coöperate with the contact plates, 108—109 of the commutator, which, in this instance, are arranged to rotate with the other rotary parts.

In the distributor the distributor points 40 112—112—112—112 are stationary and the plate or block, 113, rotates with the other rotary parts as in Fig. 1. The core, 114, also rotates with the primary coil, 115, and the secondary coil, 116, and the condenser, 45 117, rotates with the core. The battery, 118, is connected by the wire, 120, to ground and by the lead wire, 121, to a brush, 122, engaging at all times the plate, 108, of the commutator, the other plate, 109, being connected by wire, 124, with the primary coil, 115, and thence to ground, as shown by wire, 128. The condenser is inserted between the contact plates of the commutator by wires, 125, and 126. The points, 112, of 50 the distributor are connected by wires, 127, of the respective spark plug, 119. The stationary parts of the unit are connected in fixed relation as indicated by the dotted lines X^1 , and are arranged to be oscillated by the timing lever, Y^1 , also indicated in dotted lines to advance and retard the spark.

The arrows in this figure indicate the rotary parts and the direction of rotation thereof, and 130 indicates a driving shaft

to which the rotary parts are connected in any desired way, as indicated by dotted lines, Z^1 , and by which they are rotated. The secondary winding, in this figure, is shown as connected to the grounded end of 70 the primary winding instead of to the opposite end, as in Fig. 1, but this is immaterial and either arrangement can be employed.

In Fig. 3, I have shown another slightly 75 modified arrangement of my ignition unit in which the condenser is associated with the stationary parts of the unit instead of with the rotary parts, as in Figs. 1 and 2, the other elements of the unit being arranged substantially in the same manner as indicated in Fig. 2. In Fig. 3, 201 represents the cam of the periodic interrupter, which is rotary and is indicated as located 80 upon a driving shaft, 230.

The fixed and movable contacts, 203—4, of the interrupter are associated with the non-rotary parts, the latter being carried by the lever, 205, having the fiber heel, 206, for engaging the cam. The commutator 90 plates, 208—9, in this arrangement are adapted to rotate with the other rotary parts and coöperate with non-rotary brushes, 210—211, electrically connected with the fixed and movable contacts respectively.

The distributor, which is of the jump spark type, as shown in the preceding figures comprises the non-rotary distributing points, 212, the rotary part of the distributor being the block or plate, 213, which is 100 arranged to rotate with the other rotary parts of the unit. The induction coil, in this arrangement, is shown as arranged to rotate with the other rotary parts of the unit and comprises the core, 214, the primary winding, 215, and the secondary winding, 216.

In Fig. 3 the condenser indicated at 217 is associated with the non-rotary parts, as before stated, and is electrically connected 110 with the brushes, 210—211, by wires, 225—226, as shown. It will be understood that the rotary parts are connected in any desired way as indicated by dotted lines, Z^2 , to the shaft 230 for joint rotation, and the 115 non-rotary parts are also connected in any desired way as by suitable casing or frame diagrammatically represented by the dotted lines X^2 — X^2 , and are provided with means for oscillating them slightly about the axis 120 of the rotary parts to advance and retard the spark as by timing lever Y^2 also indicated in dotted lines.

The wiring of the various parts in this unit will be substantially identical with that 125 indicated in Fig. 2. The battery is indicated at 218 connected to ground by wire, 220, and by lead wire, 221, to a brush, 222, engaging at all times one of the commutator plates as 208. The other commutator plate, 130

as 209, is connected by wire 224, with the primary winding, which is grounded as indicated in the diagram by wire, 228. The secondary winding is connected to the rotary distributor plate or block, 213. The distributor points, 212, are connected by wires, 227, with the several spark plugs, 219, in the usual manner, and the spark plugs are grounded through the engine or otherwise in any well known way.

In Fig. 4 of the drawing, I have shown another modification of my system in which the unit comprises substantially the same elements arranged in a slightly different manner. In this figure, I have shown the coil associated with the non-rotary members of the unit as well as the condenser, and the distributor is provided with a brush for making contact with non-rotary distributor segments. In this figure, 301, represents the cam of the periodic interrupter, which is arranged to rotate, and 303—304 are the non-rotary contacts, in this instance, carried by spring actuated pivoted arms, 305—305, each having a fiber heel, 306, to engage the cam and cause the separation of the interrupter contacts.

The distributor comprises, in this instance, rotary distributor plates, 308—309, the plate, 308, having a portion, 308^a, extending through a central recess in the plate, 309, but insulated therefrom, and having its face flush with the face of the plate, 309.

The non-rotary portions of the commutator comprise the brushes, 310 and 311, which, in this instance, are connected with the interrupter arms, 305, at their points of pivoting, for example, and engage the faces of the portion, 308^a, of the plate, 308, and the plate, 309. The distributor comprises the non-rotary segments, 312, and the rotary brush, 313. The induction coil, in this instance, is associated with the non-rotary parts and comprises the core, 314, the primary coil, 315, and the secondary coil, 316. The rotary parts may be conveniently attached to a common shaft as 320, as indicated in the diagram as indicated by dotted lines, Z³, and the non-rotary parts may be held in fixed relation by a suitable casing frame or otherwise indicated diagrammatically by the dotted line X³, and provided with means for oscillating them about the axis of the rotary parts for timing purposes as by a timing lever indicated at Y³ in dotted lines.

317 represents the condenser, which is oscillated with the non-rotary parts, and is connected to the brushes, 310—311 as by wires, 325—326. The wiring arrangement, in this form of my invention, is as follows: 318 represents the battery, which is grounded as by wire, 320, and connected by the single lead wire, 321, with the brush, 322,

at all times in contact with one of the plates of the commutator, in this instance, plate, 309, a similar brush, 322^a, being at all times in contact with the plate, 308, of the commutator, and being connected, as by wire, 324, to the primary winding, 315, of the non-rotatable core, which is grounded in the usual manner, as indicated by the wire, 328.

The secondary winding is connected to the distributor brush, 313, the segments, 312, being connected by wires, 327, in the usual manner with the spark plugs, 319, which are grounded in a well known way.

It will be noted that in all the forms herein shown the various elements of my improved unit are brought into such close association that they may be conveniently assembled and electrically connected by the manufacturer, and adjusted so as to perform their proper functions, leaving it only necessary for the user to connect thereto the single lead wire from the battery and the distributing wires leading from the distributor to the several igniters of the internal combustion engine, thus accomplishing the new results hereinbefore particularly pointed out.

As indicated in the several figures, these elements can be combined in various ways to produce these results and the rotary parts may be conveniently arranged in conjunction with a common driving shaft as indicated in Figs. 2, 3 and 5, for example, while the non-rotary parts can be conveniently held in fixed relation with each other and in oscillating relation with the axis of the shaft by a suitable casing or frame. I do not, however, limit myself to the structural features by which the several parts are held in proper relative and operative relation.

One example of such structural features is shown, described and claimed, in my companion application executed of even date herewith.

What I claim and desire to secure by Letters Patent is:

1. In a high tension battery ignition system, in which a battery constitutes the sole source of electrical energy, a self-contained unit comprising a periodic interrupter, a commutator and a distributor, each having rotatable and non-rotatable parts, an induction coil and condenser, said parts being arranged in close relation and electrically connected, the rotatable parts of the unit being associated in fixed relation for joint rotation, and the non-rotatable parts of the unit being associated in fixed relation with each other.

2. In a high tension battery ignition system, the combination with a battery constituting the sole source of electrical energy in the system of internal combustion engines, a self-contained unit comprising a periodic interrupter, a commutator and a

distributer, each having rotatable and non-rotatable parts, said rotatable parts constituting one group of elements and being associated in fixed relation for joint rotation, said non-rotatable parts constituting another group and being associated in fixed relation with each other, an induction coil associated in fixed relation with the elements of one of said groups, and a condenser associated in fixed relation with one of said groups.

3. In a high tension battery ignition system, the combination with a battery constituting the sole source of electrical energy in the system of a self-contained unit comprising a periodic interrupter, a commutator and a distributer, each having rotatable and non-rotatable parts, an induction coil and condenser, said parts being arranged in close relation and electrically connected, the rotatable parts of the unit being associated in fixed relation for joint rotation, and the non-rotatable parts of the unit being associated in fixed relation with each other, said induction coil being associated with and rotating with the rotary parts.

4. In a high tension battery ignition system, the combination with a battery constituting the sole source of electrical energy in the system of a self-contained unit comprising a periodic interrupter, a commutator and a distributer, each having rotatable and non-rotatable parts, an induction coil and condenser, said parts being arranged in close relation and electrically connected, the rotatable parts of the unit being associated in fixed relation for joint rotation, and the non-rotatable parts of the unit being associated in fixed relation with each other, the said induction coil and the condenser being associated in fixed relation with said rotary parts and rotating therewith.

5. In a high tension battery ignition system, a self-contained unit comprising a periodic interrupter, a commutator and a distributer, each having rotatable and non-rotatable parts, an induction coil and condenser, said parts being arranged in close relation and electrically connected, the rotatable parts of the unit being associated in fixed relation for joint rotation, and the non-rotatable parts of the unit being associated in fixed relation with each other, the non-rotatable part of the periodic interrupter being capable of oscillation about

the axis of the rotary parts to advance and retard the spark.

6. In a high tension battery ignition system, a self-contained unit comprising a periodic interrupter, a commutator and a distributer, each having rotatable and non-rotatable parts, an induction coil and condenser, said parts being arranged in close relation and electrically connected, the rotatable parts of the unit being associated in fixed relation for joint rotation, and the non-rotatable parts of the unit being associated in fixed relation with each other, the non-rotary parts of the unit being capable of oscillating jointly about the axis of the rotary parts to advance and retard the spark.

7. In a high tension battery ignition system for internal combustion engines, a self-contained unit comprising a periodic interrupter having a rotatable part carrying the separable contacts and a non-rotatable cam, a commutator comprising non-rotatable contact plates and rotatable brushes, a distributer comprising non-rotatable distributing points, and a rotatable part co-acting therewith, all of said rotatable parts being associated in fixed relation, and all of said non-rotatable parts being associated in fixed relation, an induction coil associated and rotating with said rotatable parts, and a condenser associated with and rotating with said rotatable parts.

8. In a high tension battery ignition system for internal combustion engines, a self-contained unit comprising a periodic interrupter having a rotatable part carrying the separable contacts and a non-rotatable cam, a commutator comprising non-rotatable contact plates and rotatable brushes, a distributer comprising non-rotatable distributing points, and a rotatable part co-acting therewith, all of said rotatable parts being associated in fixed relation, and all of said non-rotatable parts being associated in fixed relation, an induction coil associated and rotating with said rotatable parts, and a condenser associated with and rotating with said rotatable parts, said non-rotatable parts being capable of oscillating jointly about the axis of the rotatable parts to advance and retard the spark.

In testimony whereof I affix my signature.

FRANCIS R. HOYT.
